UNITED STATES PATENT OFFICE.

HUGH C. HENDERSON, OF SAN FRANCISCO, CALIFORNIA, ASSIGNOR OF
ONE-HALF TO NEWTON M. BELL, OF SAME PLACE.

SHINGLE.

SPECIFICATION forming part of Letters Patent No. 380,203, dated March 27, 1888.

Application filed December 22, 1887. Serial No. 258,774. (No model.)

To all whom it may concern:

Be it known that I, HUGH C. HENDERSON, of the city and county of San Francisco, State of California, have invented an Improvement in 5 Shingles; and I hereby declare the following to be a full, clear, and exact description of the same.

My invention relates to certain improvements in shingles for covering houses and an 10 apparatus for preparing the same, which will be more fully explained by reference to the accompanying drawings, in which—

Figure 1 is a view of one of my shingles. Fig. 2 is a section of a roof with a few courses 15 in place. Fig. 3 is a view of the jointer. Fig. 4 is an edge view of the disk and knives.

Shingles are usually made of rectangular strips about sixteen inches long, varying in width from four to twelve inches, and having 20 a thickness of about three-eighths of an inch at one end and tapering to a thin edge at the other. The sides of these shingles are intended to be parallel; but the shingles are usually wider at the thicker end than at the thin end.

25 This is caused by careless and imperfect jointing, and is a defect difficult to avoid. The ordinary jointer consists of a wheel fitted with knives upon one side. This wheel revolves at a high speed, and the shingle is placed upon a

30 guide and pressed against the revolving knives, so that the edges are dressed off in a straight line. As the thin edge is cut away more rapidly than the thick one, it is almost impossible to prevent this tapering shape to

35 the shingles, and when laid in the usual manner, one layer overlapping another, with about four inches exposed to the weather, the shingles are usually nearly or quite in contact at the lower ends, with a space between, which

40 gradually widens from this point upwardly toward the narrow end. Within this space dirt will collect, first at the lower or narrow end and gradually accumulate toward the wider part above, forming a dam, (which dam

45 will sometimes be nearly up to the line of the overlapping layer of shingles,) which will hold the water falling upon the roof, causing it to set back into the space between the shingles, and it will run under the shingles and by cap-

50 illary attraction creep up between them, even

above the line of the course above, run through any knot-holes or cracks or through the holes made by the nails, causing the roof to leak, also causing the shingles to become damp, so as to rot easily, and the nails by which they are 55 fastened will become rusted off, so that the shingles will come out, and thus make other leaks.

The above is only true in part, as it is not the universal rule that shingles are narrower 60 at the thin end; but even if they had parallel sides the objection would still hold, as in laying the roof a carpenter cannot be at the pains to have the thick edges all to an exact line, some of the spaces would be even, some wedge- 65 shaped, closed at the lower end, and some the reverse of this. In any event the space is narrow and forms a ready receptacle for dirt or paint, (if the roof is painted,) partially closing it up, producing the result stated. 70

The salient point is that the space is narrow and readily fills up, and the fact that it is sometimes in the form of a wedge, tending to aggravate the difficulty, is simply an incident of and not the prime cause of the defect. 75

My invention is designed to overcome this difficulty. It consists in forming the shingles with a portion of the lower end of each edge cut away in a bevel or inclined form, so as to present a diverging or widening opening at 80 the lower end of the shingles.

A is an ordinary shingle, and the lower end of this shingle has its sides beveled or cut away, as shown at B, the incline commencing at a point about four inches or more from the 85 thicker end of the shingle. This incline is readily formed by fixing to the face of the revolving disks which form the jointer an additional set of knives, D. These knives have their inner ends at the same distance above the 90 face of the disk as the knives E, which form the straight edge of the shingle, overlapping enough to make a proper joint, and the outer ends of the knives D are as much higher from the face of the disk C as will be needed to cut 95 away the thicker end of the shingle, so as to form the beveled portion B, before described. In place of the two sets of separate knives, single knives may be used having the outer end raised from the surface, so as to form the 100

angle or bevel, as before described. By this construction the shingles are readily jointed, the work being done as rapidly as in the ordinary straightjointing. These shingles, when 5 laid so as to expose about four inches of the thicker end in the usual manner, will have a widening space between them commencing near the lower end of the course above and opening outwardly to the exposed end of the 10 shingles, which allows all the water which falls from the roof to run off rapidly and easily, and also enables me to thoroughly paint all portions of the roof and these intermediate spaces as well. 15 I am aware slates of different shapes, including lengthened octagonal form, have been constructed and used in conjunction with special fastening devices as a covering for roofs. I therefore do not claim such constructions, as 20 in my case the shingle has parallel edges for about two-thirds of its length, which then converge slightly the remaining distance to form

a widening space between contiguous shingles, for a purpose previously stated.

Having thus described my invention, what I 25 claim as new, and desire to secure by Letters Patent, is—

1. As a new article of manufacture, a shingle having approximately-parallel edges for about two-thirds of the length from the thin 30 end, and converging slightly the remaining distance, substantially as herein described.

2. The shingle having the edges at the thicker end made slightly diverging to a point about one-third of the length from the thicker end 35 and approximately parallel from that point to the thinner end, substantially as herein described.

In witness whereof I have hereunto set my hand.

HUGH C. HENDERSON.
